CLOCK

Frank Gianascol, Lynn, Mass.

Application May 23, 1951, Serial No. 15,294

Term of patent 7 years

(Cl. D42—7)

To all whom it may concern:

Be it known that I, Frank Gianascol, a citizen of the United States, residing at Lynn, State of Massachusetts, have invented a new, original, and ornamental Design for a Clock, of which the following is a specification, reference being had to the accompanying drawing, forming a part hereof.

Fig. 1 is a front elevational view of a clock, showing my new design; and

Fig. 2 is a side elevational view, the essential features of the design being shown in full lines.

The hour markings are lined to indicate contrasting colors.

I claim:

The ornamental design for a clock, as shown and described.

FRANK GIANASCOL.
